CLAIM

The ornamental design for a motor driven toy can, as shown and described.

DESCRIPTION

FIG. 1 is a front perspective view of a motor driven toy can showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view thereof in transitory condition;

FIG. 8 is a front perspective view of a modified embodiment of the design shown in FIGS. 1 through 7; and,

FIG. 9 is a front perspective view of a second modified embodiment of the design shown in FIGS. 1 through 7.

FIG. 2
FIG. 1

FIG. 4

FIG. 3

FIG. 7

FIG. 5

FIG. 6

FIG. 9

FIG. 8
